UNITED STATES PATENT OFFICE.

ELMER HAUSE, OF TECUMSEH, MICHIGAN.

DESIGN FOR A WINDOW-FASTENING STRIP.

SPECIFICATION forming part of Design No. 24,516, dated July 30, 1895.

Application filed June 13, 1895. Serial No. 552,732. Term of patent 7 years.

To all whom it may concern:

Be it known that I, ELMER HAUSE, a citizen of the United States, residing at Tecumseh, county of Lenawee, State of Michigan, have 5 invented and produced a new and original Design for a Window-Fastening Strip, of which the following is a full, clear, and exact description, reference being had to the accompanying drawings, which form a part of 10 this specification.

My invention consists of the design herein-after specified and claimed, and illustrated in the drawings, in which—

Figure 1 is a view in perspective of the 15 strip, showing my design. Fig. 2 is a longitudinal section.

The leading feature of my design consists of an elongated window-fastening strip A, formed with a series of tongues a, stamped

out therefrom longitudinally of the strip, one 20 above another, forming a corresponding series of orifices a' in the strip. These orifices, as shown in the drawings, are made of greater width at the top than at the bottom, the tongues being of corresponding form, and my 25 design pertains more particularly to the strip having such a form or shape of said orifices and tongues.

What I claim is—

The design for a window fastening strip as 30 herein shown and described.

In testimony whereof I sign this specification in the presence of two witnesses.

ELMER HAUSE.

Witnesses:

GEO. W. MARSDEN,
FRANK B. BAUER.
